(57) **CLAIM**

The ornamental design for a tip of umbrella, as shown and described.

DESCRIPTION

FIG. 1 is a front, right, top perspective view of a tip of umbrella, showing my new design;

FIG. 2 is a rear, left, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view thereof; and,

FIG. 8 is a bottom plan view thereof.

The dashed broken lines in the figures are for the purposes of illustrating portions of the tip of umbrella and form no part of the claimed design.

1 Claim, 8 Drawing Sheets(56)
